UNITED STATES PATENT OFFICE.

NAPOLEON DU BRUL, OF CINCINNATI, OHIO, AND ALBERT DU BRUL, OF FORT THOMAS, KENTUCKY, ASSIGNORS TO THE MILLER DU BRUL AND PETERS MFG. CO., OF CINCINNATI, OHIO, A CORPORATION OF OHIO.

PROCESS OF CARDING TOBACCO.

1,107,047.

Specification of Letters Patent. Patented Aug. 11, 1914.

Application filed December 21, 1912. Serial No. 738,086.

To all whom it may concern:

Be it known that we, NAPOLEON DU BRUL, a citizen of the United States, residing at Cincinnati, in the county of Hamilton and 5 State of Ohio, and ALBERT DU BRUL, a citizen of the United States, residing at Fort Thomas, in the county of Campbell and State of Kentucky, have invented certain new and useful Improvements in Processes 10 of Carding Tobacco, of which the following is a specification.

The object of our process is to card tobacco and form it into a body uniform as to quality and condition.

15 It is a well known fact that when tobacco is placed in a hopper under conditions in which its weight can exert a material influence upon its presentation to a feeder or forming roll, due to the gradual reduction 20 in the quantity of the material in the hopper, as well as climatic and other conditions, there is a serious lack of uniformity in the quantity of tobacco picked up by the feed or former roll with the result that serious irregularity exists in the distribution of the 25 tobacco in forming a prescribed body of the carded tobacco.

Our invention has for its object to overcome these conditions in order to obtain a 30 more regular feeding of the material and the formation of a body from said tobacco of uniform thickness and density throughout its structure.

The figure of the drawing is a vertical 35 section of one form of machine designed to carry out our process.

Referring generally to the figure, 1 represents a hopper having its bottom formed by an endless belt 2, driven in the direction to 40 advance material to a feed roll 3, there being a series of these restraining means which are in the shape of raking arms on said shaft, the lower ends of said arms being deflected as shown.

45 6 is a tamping or packing device mounted on the shaft 5 and adapted to be swung in an arc with said shaft so as to have impact against the periphery of the feed roll 3.

7 is a dresser roll for acting with the feed roll 3.

8 is a stripping roll and 9 is a replacing roll adapted to press the tobacco firmly upon the feed roll to limit the effect of the stripping roll on the tobacco with which it is immediately engaging.

In carrying out our process the tobacco to be carded is placed on the conveyer belt 2 in the hopper 1, by means of which the bulk of the tobacco is fed toward the feeding roll, but in order to prevent the tobacco under treatment banking against the feed roll and at intervals to be rolled about as a mass, without the proper amount being picked up by the teeth, which results in the tobacco being torn away from the main bulk 65 and reduced to fine particles, and being fed in irregular quantities to the roll, we retard or restrain the progress of the mass of tobacco by the oscillation of the arms 4 which have the effect, generally speaking, of a rake, thereby raising the tobacco and restraining it from advancing to the feed roll and at the same time loosening the material up, or fluffing it and preventing it from matting down or packing too closely in the space 75 through which it advances to the feed roll. Even with the feeding of the substantially uniform quantity of tobacco to the feeding roll, the presentation of the charge of tobacco to the stripping roll is not always uniform in thickness, owing to the difficulty of causing the tobacco to enter firmly and uniformly between the carding teeth on the feed roll 3. To overcome this objection we

tamp the tobacco by means of the tampers 6 on the feed roll which has the effect of packing the tobacco firmly down into the spaces between the teeth and developing a uniform layer or charge of tobacco on the feed roll and giving it the particular density desired. 85 After the tobacco has been tamped, all surplus tobacco is removed from the feeding roll 3, by means of the dresser roll 7. By this dressed roll we are enabled to remove all that portion of the tobacco lying outside 90 of the layer desired to be delivered by the

feed roll to the stripper 8. The dresser roll co-acts with the feed roll at a point immediately after the tamping point, as it is thereby better enabled to pick off and remove the excess tobacco at this point without disturbing the portion of the charge desired to be retained on the feed roll.

What we claim is:

The process of forming a tobacco filler
10 for cigarettes which consists in fluffing the
tobacco in bulk, feeding the fluffed tobacco
to a feeder, tamping the fluffed tobacco on

said feeder to a uniform density, dressing
the tamped tobacco, and finally stripping
the tamped tobacco from the feeder. 15

The foregoing specification signed at Cincinnati Ohio this 10th day of December, 1912.

NAPOLEON DU BRUL.
ALBERT DU BRUL.
